UNITED STATES PATENT OFFICE.

JOHN W. McAULIFFE, OF CHICAGO, ILLINOIS.

SANITARY SEAT FOR WATER-CLOSETS.

937,164.

Specification of Letters Patent. Patented Oct. 19, 1909.

Application filed November 16, 1908. Serial No. 462,859.

To all whom it may concern:

Be it known that I, JOHN W. McAULIFFE, a citizen of the United States, residing at Chicago, county of Cook, State of Illinois, 5 have invented a certain new and useful Improvement in Sanitary Seats for Water-Closets, and declare the following to be a full, clear, and exact description of the same, such as will enable others skilled in the art 10 to which it pertains to make and use the same, reference being had to the accompanying drawings, which form a part of this specification.

In the usual form of water-closet wherein 15 there is employed a hinged seat there has always been the serious objection of wetting the under side of the seat at the front thereof. This wetting renders the seat unsanitary and often distorts it due to absorption 20 of the liquid by the wood of which the seat is composed. It has been proposed to make seats of metal, porcelain or other sanitary material which will not absorb the water or other liquids which may come upon it, 25 but this has been found impracticable because of the high heat-conductivity of such materials which make seats composed thereof uncomfortable. Therefore resort has been had to cutting away the front portion of 30 the seat and providing the bowl with an upwardly extending projection to fill the opening so formed. This arrangement not only weakens the seat, but it is inapplicable to any type of bowl which does not have the 35 upwardly-extending projection: furthermore, it is uncomfortable in that the person of the user is apt to be pinched between the seat and the projection.

The object of my invention is to provide 40 a simple and novel arrangement overcoming the original objection of unsanitariness in water-closet seats.

A further object of my invention is to provide a sanitary arrangement applicable 45 to any usual type of water-closet.

To the above end I have provided a novel seat, applicable to any ordinary form of bowl, which will be free from the objections to the old wooden seat and also from the 50 disadvantages inherent in sanitary seats made of materials of high-heat conductivity.

The various features of novelty which characterize my invention will hereinafter be pointed out with particularity in the 55 claims; but, for a full understanding of my

invention and of its various objects and advantages, reference may be had to the following detailed description taken in connection with the accompanying drawing, 60 wherein:

Figure 1 is a top plan view of a water-closet bowl having a seat arranged in accordance with one form of my invention; Fig. 2 is a bottom plan view of the seat; Fig. 3 is a view showing a portion of the 65 front edge of the seat; Fig. 4 is a section taken on line y—y in Fig. 3; and Fig. 5 is a section taken on line z—z of Fig. 2.

Referring to the drawing, A represents a bowl and B a detachable seat hinged thereto 70 as at b, although any other usual or preferred arrangement for securing the seat may be employed. In the preferred form, I make use of a metallic ring or frame on which are supported side pieces composed 75 of a material of low heat-conductivity; the ends of the side pieces being separated from each other at points where they might become wet, as at the front or back of the seat opening. In the particular arrangement 80 illustrated, I have shown a separation of the side pieces both at the front and at the back, although I do not desire to be limited to this most highly developed form.

The two side pieces are indicated at C and 85 D and, fitting between the separated ends thereof, are blocks or sections E and F which form therewith a continuous ring bounding the seat-opening, B¹. The lengths of the blocks or sections, measured circumferentially of the seat opening, are such as to 90 cover the zones to be protected. The blocks may have any desired cross-section in the radial direction and may or may not take the shape of the adjacent portions of the side 95 pieces. In the arrangement shown, the blocks are depressed below the upper surface of the seat so that the person of the user does not come in contact therewith. In this form they are preferably inclined downwardly from the outer edges toward the inner edges, and may also be provided with raised beads e and f at the outer edges; consequently any water or other liquid which comes upon the blocks will run down into 100 the bowl and soiling of the floor adjacent to the bowl will be avoided.

The two sanitary blocks or sections are connected together by means of arms G and H which underlie the side pieces and, to 110

gether with the sections, form a skeleton frame or ring. The side pieces are secured to this frame or ring in any suitable manner, as, for example, by means of screws. I. 5 This makes a cheap as well as a durable and sanitary construction, since the frame or ring may be cast or otherwise formed of metal and the side pieces be molded if desired. The exposed portions of the frame 10 may be painted, galvanized or coated with porcelain, according to the grade or quality of seat desired. The hinge members *b* are preferably connected with the metal frame as it is better adapted to bear the strain 15 than the portions of low heat conductivity. It will now be seen that I have provided a seat which is wholly sanitary, while at the same time it will not subject the user to the discomforts of prior arrangements seeking 20 this end; furthermore, it is strong and durable and may be applied to substantially all types of bowls.

While I have illustrated and described in detail only a single preferred form which 25 my invention will take, it will of course be understood that, broadly considered, my invention may be embodied in various other forms containing many structural details which will readily suggest themselves to 30 those skilled in the art; and by the terms of the definitions of my invention constituting the appended claims I intend to cover all such forms.

Having now described my invention, what

I claim as new and desire to secure by Letters Patent, is:

1. A movable sanitary seat comprising a continuous metal frame bounding an opening, and side pieces composed of a material of low heat-conductivity mounted upon the side portions of the frame, said frame having upwardly projecting sections fitting between the ends of the said side pieces.

2. A movable sanitary seat comprising a continuous metal frame bounding an opening, and side pieces composed of a material of low heat-conductivity mounted upon the side portions of the frame, said frame having upwardly projecting sections fitting between the ends of the side pieces and having 50 their upper surfaces inclined upwardly from the inner edges of the said sections.

3. A movable sanitary seat comprising a continuous metal frame bounding an opening, said frame having sections composed of 55 a material of low heat-conductivity mounted thereon, the adjacent ends of said sections being separated from each other at one end of the seat, and said frame having an upwardly projecting portion fitting between 60 said ends.

In testimony whereof, I sign this specification in the presence of two witnesses.

JOHN W. McAULIFFE.
